N. WATERMAN, OF TOLEDO, OHIO.

Letters Patent No. 64,173, dated April 23, 1867.

IMPROVED FOLDING CHAIR.

The Schedule referred to in these Letters Patent and making part of the same.

TO ALL WHOM IT MAY CONCERN:

Be it known that I, N. WATERMAN, of Toledo, in the county of Lucas, and State of Ohio, have invented new and "Improved Folding Chairs;" and I do hereby declare that the following is a full, clear, and exact description thereof, which will enable those skilled in the art to make and use the same, reference being had to the accompanying drawings, forming part of this specification.

The present invention relates to that class of chairs in which the seat-frame, whether covered with a rigid or flexible material, is hinged to the front side of the chair, and is supported by its rear edge upon a cross-round in the back-frame; and the invention consists in a novel manner of connecting the back edge of the chair-seat to the round of the back-frame, and in so curving or shaping the back legs to the chair-frame, that, when the chair-frame is brought to a horizontal position, or nearly so, they will form a rest for the chair-seat. In the accompanying plate of drawings my improved folding chair is illustrated—

Figure 1 being a central longitudinal vertical section through the chair.

Figure 2, a side view of the chair with its seat in its lowest position.

A, in the drawings, represents the frame constituting the back to the chair, and by the lower portions B, of its side pieces C, forming the front legs to the chair. D the back legs, formed by the curved side pieces E that are pivoted at F, to the side pieces C, forming the front legs so as to turn thereon. G the seat-frame, pivoted by its front rail L to the upper ends of the back legs D, with its hind or rear rail or strip H hung to the round I of the back-frame, through hooks J inserted in the said strip H. The width of the seat-frame is such as to fit within and between the side pieces of the back-frame A. In fig. 1 the chair is shown as in an upright position, but in fig. 2 it is represented as in its lowest position, the seat-frame G then resting upon the pieces constituting the back legs, the curve of which is such as to then afford a suitable rest or support therefor.

I claim as new, and desire to secure by Letters Patent—

The combination of the seat G, and legs B D, whereby the back legs D, fold on the front legs B, and the seat G, passing through between the side pieces C, above the round I, fold on the hind legs D, of the chair, substantially as described for the purpose specified.

N. WATERMAN.
